(57) **CLAIM**

The ornamental design for a chemical diffusing apparatus, as
shown and described.

DESCRIPTION

FIG. 1 is a front view of the chemical diffusing apparatus of
the present invention, the hook element being removed for
ease of illustration;

FIG. 2 is a right side view, the hook element removed for
ease of illustration;

FIG. 3 is a left side view, the hook element removed for ease of
illustration;

FIG. 4 is a top view, the hook element removed for ease of
illustration;

FIG. 5 is a bottom view, the hook element removed for ease of
illustration;

FIG. 6 is a back view, the hook element removed for ease of
illustration;

FIG. 7 is a cross-sectional view taken along lines VII—VII
in FIG. 1, the hook element removed for ease of illustration;

FIG. 8 is a perspective view, the hook element removed for
ease of illustration;

FIG. 9 is a view showing the chemical diffusing apparatus
in a standing position; and,

FIG. 10 is a view showing the chemical diffusing apparatus
is a hanging position.
